MOTOR OPERATED KINESITHERAPY
DEVICE

Owen K. Murphy, Adamsville, Pa.

Application June 19, 1952, Serial No. 294,458

4 Claims. (Cl. 128—36)

1

This invention relates to a motor operated kinesitherapy device and more particularly to a simple and durable device of this character with an applicator having gyratory motion and which device can be effectively used for treatments of the human body.

This application is a companion to my copending application Serial No. 294,457 filed June 19, 1952 for Cushion Type Motor Operated Kinesitherapy Device.

As hereinafter more fully described the present invention is concerned with such a device having a motor operated gyrator and which device can be held in the hand and applied to different parts of the body or may be embodied in a device having the form of a cushion as shown in my said companion application. In such appliances as heretofore made, considerable difficulty has been experienced in providing an instrument which is simple, rugged and highly effective. Because of the gyratory motion, the bearings of the motor are particularly susceptible to destructive action, and undue wear in these parts leads to other failures. In the device embodying the present invention a novel and simple construction is provided for mounting the entire motor unit as an entity, and with a measure of resiliency or freedom of movement which eliminates the cause of failure and at the same time provides a motion or action having both a pleasing and a therapeutic effect.

Accordingly, one of the objects of the present invention is to provide such a motor operated kinesitherapy device which will operate without change in characteristics for a long period of time and which has both a pleasing and therapeutic effect.

Another object is to provide such a device which is composed of simple and low cost parts that can readily be put together.

Another object is to provide such a device composed of sheet metal housing or shell sections which can be highly polished and readily kept in a sanitary condition.

Another object is to provide such a device which has ends of different degrees of bluntness to facilitate application to different parts of the body.

Another object is to provide such a device having a readily removable rubber pad particularly desirable for facial application.

Another object is to provide such a device in which the motor is adequately ventilated and its brushes readily accessible.

Other objects and advantages of the invention

will be apparent from the following description and drawings in which:

Fig. 1 is a side elevational view of a therapeutic device adapted to be held in the hand of the user and applied to different parts of the body.

Fig. 2 is a vertical longitudinal section through the hand device shown in Fig. 1.

Fig. 3 is a transverse section taken generally on line 3—3, Fig. 2.

Fig. 4 is a fragmentary view similar to Fig. 2 and showing one of the casing or shell parts disassembled from the motor to illustrate the original shape of the rubber ring mounting for the motor contained within the casing sections.

15 In the form of the invention illustrated the numeral 10 represents an electric motor having a generally cylindrical casing 11 and a motor shaft 12. A fan 13 is mounted on one end of the motor shaft 12, the blade of this fan being shaped to move the air longitudinally through the casing 11 of the electric motor for the purpose of cooling the same. The fan includes a hub 14 from which its blades 15 radiate, and screwed into the fan hub 14 is a screw 16 which projects radially and has a head 17 at its outer end. One or more weights 18 are carried by the screw 16, these weights being preferably of washer-like form and held against the screw head 17 by a lock nut 19. The screw 16 and its weights 18 provide an eccentric weight on the motor shaft 12 which tends to gyrate the motor shaft and the motor as a function of its operation.

An important feature of the invention resides in the provision of a pair of rubber rings 20 surrounding each of the opposite ends of the motor casing 11. These rings are preferably cementitiously secured, as indicated at 22, to the motor casing and provide a resilient radial extension of the motor casing thereof.

40 An important feature of the invention resides in the unstressed form of the rubber rings 20. Thus, upon reference to Fig. 4, the rubber rings 20 are of frusto-conical form with conical faces 21 converging toward the end of the motor.

45 This convergence is for the purpose of facilitating the insertion of the motor unit into the two parts 25 and 26 of the housing or shell of the device. A layer 27 of suitable cement is preferably applied to the peripheral faces 21 of the 50 rubber rings before such insertion to secure the housing sections to the rubber rings and motor casing. Each of these housing or shell parts is made of one piece of sheet metal and the part 25 includes an open ended cylinder 28 terminating in 55 a hemispherical end head 29 with an annular

row of ventilating openings 30 arranged along the line of juncture between the cylindrical and hemispherical parts of this housing section.

The other housing or shell section includes a cylindrical part 31, open at one end and terminating at its other end in an inward extension 32. The central part of this inward extension 32 is axially continued to form a tapered nose 33 having a rounded end 34. The inward extension 32 of the housing section 26 is provided with an annular series of ventilating holes 35 and also a switch 36 mounted in this inward extension. This inward extension 32 also carries the fitting 38 for the lead in wire 39, this fitting having the usual spring 40 for preventing abrupt bending of the lead in wire. The cylindrical part of this casing section can also have the usual opposite holes 41 to permit ready replacement of the brushes (not shown) of the motor.

For massaging the face it is desirable to have a soft pad attached to the tool and to this end the tool is provided with a rubber cup 42 of shallow concavo-convex form with an integral rubber ring 43 attached centrally to its convex side. This ring is of such size as to be capable of being slipped over the tapered nose 33 of the tool and to be held thereon by the friction of the slightly distended rubber ring 43.

In assembling the tool as above described the motor 10 with the conical faces 21 of the two rubber rings 20 converging toward the ends of the motor and with these faces coated with the adhesive 27 have forcibly fitted thereon the cylindrical portions 28 and 31 of the two housing sections 25 and 26. These two housing sections are forced over the rubber rings 21 so that their rims mate with each other as best shown in Fig. 2. In so forcing these housing sections 25 and 26 into rim mating relation with each other around the motor the rubber rings 21 are compressed so as to assume a cylindrical form as best shown in Fig. 2. This displacement of the rubber places these rubber rings under stress.

When current is supplied to the lead in wire 39 and the switch 36 turned on, the eccentric weights 18 on the motor shaft 12 tend to gyrate this motor shaft as well as the casing 11 of the motor. This gyroscopic motion is transmitted through the rubber rings 20 to the housing sections 25 and 26 and when applied to the body or held in the hand the entire casing has a beneficial gyroscopic motion for the therapeutic use. Particularly for facial massage the rubber ring 43 of the concavo-convex rubber pad 42 can be slipped over the tapered nose 33 of the housing and this pad can be applied to the face.

It will be noted that the subject of the invention includes a housing, a motor disposed within the housing in fully spaced relation to the walls thereof and having a relatively stationary part and rotary part and that the rotary part has a predetermined, mechanical, rotary unbalance of substantial amount well in excess of any accidental unbalance due to inaccuracy in manufacture. It will further be noted that in the invention a plurality of soft, resilient, cushion rings are provided in axially spaced relation around the stationary part of the motor and are interposed under stress between the stationary part and the housing walls to serve as the sole and floating support between the motor and housing whereby rotation of the unbalanced rotary part of the motor will cause a gyroscopic bodily movement of the motor in a relatively small, closed

loop path which is transmitted through the cushion rings to the housing.

I claim:

- 5 1. A therapeutic device adapted to be held in the hand, comprising two one piece generally cylindrical, rigid, hollow, metal housing sections having opposing open ends adapted to be brought into mating relation with each other to provide a generally cylindrical housing, the opposite end of each of said housing sections being closed by an integral circular end head, an electric motor disposed within the chamber in fully spaced relation to the walls of said housing and extending across the mating ends of said housing sections, said motor having a relatively stationary generally cylindrical casing arranged with its axis lengthwise of said chamber and having a rotary shaft journaled coaxially within said casing, an eccentric weight driven by said shaft and providing a predetermined, mechanical rotary unbalance well in excess of any accidental unbalance due to inaccuracy of manufacture, and a pair of axially spaced, soft, resilient cushion rings each encircling a corresponding end of 10 said motor casing and interposed under stress between said motor casing and one of said housing sections, and serving as the connector between said housing sections and also as the sole and floating support between said motor and said housing whereby rotation of said eccentric weight will cause a gyroscopic movement of said motor in a relatively small, closed-loop path which is transmitted through said rings to said housing.
- 20 2. A therapeutic device adapted to be held in the hand, comprising two one piece generally cylindrical, rigid, hollow, metal housing sections having opposing open ends adapted to be brought into mating relation with each other to provide a generally cylindrical housing, the opposite end of each of said housing sections being closed by an integral circular end head, an electric motor disposed within the chamber in fully spaced relation to the walls of said housing and extending across the mating ends of said housing sections, said motor having a relatively stationary generally cylindrical casing arranged with its axis lengthwise of said chamber and having a rotary shaft journaled coaxially within said casing, an eccentric weight driven by said shaft and providing a predetermined, mechanical, rotary unbalance well in excess of any accidental unbalance due to inaccuracy of manufacture, a pair of axially spaced, soft, resilient cushion rings each encircling a corresponding end of 25 said motor casing and interposed under stress between said motor casing and one of said housing sections, and serving as the connector between said housing sections and also as the sole and floating support between said motor and said housing whereby rotation of said eccentric weight will cause a gyroscopic movement of said motor in a relatively small, closed-loop path which is transmitted through said rings to said housing.
- 30 3. A therapeutic device adapted to be held in the hand, comprising two one piece generally cylindrical, rigid, hollow, metal housing sections having opposing open ends adapted to be brought into mating relation with each other to provide a generally cylindrical housing, the opposite end of each of said housing sections being closed by an integral circular end head, an electric motor disposed within the chamber in fully spaced relation to the walls of said housing and extending across the mating ends of said housing sections, said motor having a relatively stationary generally cylindrical casing arranged with its axis lengthwise of said chamber and having a rotary shaft journaled coaxially within said casing, an eccentric weight driven by said shaft and providing a predetermined, mechanical, rotary unbalance well in excess of any accidental unbalance due to inaccuracy of manufacture, a pair of axially spaced, soft, resilient cushion rings each encircling a corresponding end of 35 said motor casing and interposed under stress between said motor casing and one of said housing sections, and serving as the connector between said housing sections and also as the sole and floating support between said motor and said housing whereby rotation of said eccentric weight will cause a gyroscopic movement of said motor in a relatively small, closed-loop path which is transmitted through said rings to said housing.
- 40 4. A therapeutic device adapted to be held in the hand, comprising two one piece generally cylindrical, rigid, hollow, metal housing sections having opposing open ends adapted to be brought into mating relation with each other to provide a generally cylindrical housing, the opposite end of each of said housing sections being closed by an integral circular end head, an electric motor disposed within the chamber in fully spaced relation to the walls of said housing and extending across the mating ends of said housing sections, said motor having a relatively stationary generally cylindrical casing arranged with its axis lengthwise of said chamber and having a rotary shaft journaled coaxially within said casing, an eccentric weight driven by said shaft and providing a predetermined, mechanical, rotary unbalance well in excess of any accidental unbalance due to inaccuracy of manufacture, a pair of axially spaced, soft, resilient cushion rings each encircling a corresponding end of 45 said motor casing and interposed under stress between said motor casing and one of said housing sections, and serving as the connector between said housing sections and also as the sole and floating support between said motor and said housing whereby rotation of said eccentric weight will cause a gyroscopic movement of said motor in a relatively small, closed-loop path which is transmitted through said rings to said housing.
- 50 5. A therapeutic device adapted to be held in the hand, comprising two one piece generally cylindrical, rigid, hollow, metal housing sections having opposing open ends adapted to be brought into mating relation with each other to provide a generally cylindrical housing, the opposite end of each of said housing sections being closed by an integral circular end head, an electric motor disposed within the chamber in fully spaced relation to the walls of said housing and extending across the mating ends of said housing sections, said motor having a relatively stationary generally cylindrical casing arranged with its axis lengthwise of said chamber and having a rotary shaft journaled coaxially within said casing, an eccentric weight driven by said shaft and providing a predetermined, mechanical, rotary unbalance well in excess of any accidental unbalance due to inaccuracy of manufacture, a pair of axially spaced, soft, resilient cushion rings each encircling a corresponding end of 55 said motor casing and interposed under stress between said motor casing and one of said housing sections, and serving as the connector between said housing sections and also as the sole and floating support between said motor and said housing whereby rotation of said eccentric weight will cause a gyroscopic movement of said motor in a relatively small, closed-loop path which is transmitted through said rings to said housing, a cementitious bond between said rings and motor casing, and a cementitious bond between each of said rings and a corresponding housing section.
- 60 6. A therapeutic device adapted to be held in the hand, comprising two one piece generally cylindrical, rigid, hollow, metal housing sections having opposing open ends adapted to be brought into mating relation with each other to provide a generally cylindrical housing, the opposite end of each of said housing sections being closed by an integral circular end head, an electric motor
- 65
- 70
- 75

disposed within the chamber in fully spaced relation to the walls of said housing and extending across the mating ends of said housing sections, said motor having a relatively stationary generally cylindrical casing arranged with its axis lengthwise of said chamber and having a rotary shaft journaled coaxially within said casing, an eccentric weight driven by said shaft and providing a predetermined, mechanical, rotary unbalance well in excess of any accidental unbalance due to inaccuracy of manufacture, a pair of axially spaced, soft, resilient cushion rings each encircling a corresponding end of said motor casing and interposed under stress between said motor casing and one of said housing sections, and serving as the connector between said housing sections and also as the sole and floating support between said motor and said housing whereby rotation of said eccentric weight will cause a gyratory movement of said motor in a relatively small, closed-loop path which is transmitted through said rings to said housing, a cementitious bond between said rings and motor casing, and a cementitious bond between each of said rings and a corresponding housing section, and said rings in the normal unstressed condition thereof being of frusto-conical form with their peripheral faces converging in opposite directions and toward the corresponding ends of said motor casing to facilitate insertion thereof into said housing sections.

4. A therapeutic device adapted to be held in the hand, comprising two generally cylindrical, rigid, hollow, metal housing sections having op-

posing open ends adapted to be brought into mating relation with each other to provide a generally cylindrical housing, an electric motor disposed within the chamber in fully spaced relation to the walls of said housing, said motor having a relatively stationary generally cylindrical casing arranged with its axis lengthwise of said chamber and having a rotary shaft journaled coaxially within said casing, an eccentric weight driven by said shaft and providing a predetermined, mechanical, rotary unbalance well in excess of any accidental unbalance due to inaccuracy of manufacture, a pair of axially spaced, soft, resilient cushion rings each encircling a corresponding end of said motor casing and interposed under stress between said motor casing and said housing walls, and serving as the sole and floating support between said motor and said housing whereby rotation of said eccentric weight will cause a gyratory movement of said motor in a relatively small, closed-loop path which is transmitted through said rings to said housing, one of said housing sections being formed with an axially elongated nose, and a concavo-convex rubber pad having an integral ring projecting from its convex face and adapted to be fitted frictionally over said nose.
